DOOR LOCK

John F. Ching, Berkeley, Calif.

Application June 21, 1940, Serial No. 341,707

7 Claims. (Cl. 292—169)

This invention relates to locks for doors or other similar closures.

It is an object of the invention to provide a door lock constructed, substantially in its entirety, of die-formed sheet metal.

Another object of the invention is to provide a lock structure which may be mounted in a door merely by providing the latter with a pair of axially intersecting bored holes.

A further object of the invention is to provide a simplified door lock of the type in which depression of a push-button, contained in one of the knobs, will operate mechanism for securing the lock bolt against retraction.

Still another object of the invention is to provide a simplified construction for door locks of the type described.

A still further object of the invention is to provide novel bolt-dogging mechanism in a door lock of the class previously referred to.

Yet another object of the invention is to provide, in a door lock of the class described, novel guide means for supporting the retractile latch bolt.

The invention possesses other objects and features of advantage, which, together with the foregoing, will be specifically brought out in the detailed description of the invention hereunto annexed. It is to be understood that the invention is not to be limited to the specific form thereof herein shown and described as various other embodiments thereof may be employed within the scope of the appended claims.

Referring to the drawings:

Figure 1 is a vertical sectional view, of the door lock of my invention, taken axially of the knob shaft. The dogging mechanism in this view is shown in its released position.

Figure 2 is a fragmental view, partly in front elevation and partly in vertical section, of a portion of the structure of Figure 1 illustrating the action of the latch trigger in passing from its released to its engaged positions.

Figure 3 is a vertical sectional view taken transversely of the knob shaft. The plane in which the view is taken is indicated by the line 3—3 of Figure 1.

Figure 4 is a view, similar to Figure 1, showing the dogging mechanism in its engaged position.

Figure 5 is a vertical sectional view taken transversely of the knob shaft and in the plane indicated by the line 5—5 of Figure 4. The view illustrates the means for retaining the latch trigger in its engaged position.

Figure 6 is a view, similar to Figure 5, showing the manner in which the latch trigger is released.

Figure 7 is a perspective view of the plunger.

Figure 8 is a vertical sectional view of the door lock taken axially of the bolt and in the plane indicated by the line 8—8 of Figure 1.

Figure 9 is a top plan view of the knob shaft.

Figure 10 is an end elevational view of the knob shaft shown in Figure 9.

Figure 11 is a top plan view of the inner knob ferrule.

Figure 12 is an end elevational view of the ferrule shown in Figure 11.

Figure 13 is a bottom plan view of the ferrule shown in Figure 11.

The door lock of my invention is designed for use in a wooden door 14 provided with a circular aperture 16, bored completely through the door from the inner side 17 to the outer side 18 thereof and spaced inwardly from the edge 19 thereof, and with a bore 21 positioned medially of and paralleling the sides of the door and extending from the edge 19 to normally intersect the aperture 16.

25 Positioned in and concentric with the aperture 16 is a tubular lock body 22 having an opening 23 in the wall thereof concentric with the axis of the bore 21 and in which is positioned a pair of axially spaced plates 24 and 26. The plates 24 and 26 may be secured to the body 22 in any accepted manner but are preferably provided with peripheral notches 27 into which are pressed tabs 28 struck inwardly from the wall of the lock body. Each tab 28 is provided with integral ears 29 which extend beyond the notches 27 over the opposite sides of the plates. The engagement of the tabs 28 in the notches 27 secures the plates and the lock body together against relative rotational motion while the ears 29 prevent displacement of the plates relative to each other or axially of the lock body. The plate 24 is provided with a central bored hub 31 and the plate 26 with a concentric opening 32 having a pair of diametrically opposed peripheral notches 33, and both plates are provided, adjacent their peripheral edges, with two or more internally threaded tubular bosses 34. Circular escutcheon plates 36, having peripherally flanged central openings 37 axially aligned with the opening 16, are each provided with radially spaced holes through which screws 38, having their inner threaded ends engaged in the plate bosses 34, pass so as to secure the escutcheon plates to the opposite sides of the door.

40 55 Journalized in the hub 31 of the plate 24, and

extending concentrically through the escutcheon plate openings 39 and the opening 32 of the plate 26, is a tubular knob shaft 39, best shown in Figure 9, having a pair of diametrically opposed longitudinally extending slots 41 which open at one end of the shaft and which terminate at a point substantially medially of the ends thereof. Both slots 41, at their inner ends, are provided with enlarged rectangular recesses 42 and one of the slots, at the point where it intersects the end of the shaft, is provided with a notch 43 which is slightly wider than the slot 41. The other end of the shaft 39 is provided with an axially extending opening 44 in which lies an integral portion of the tube wall forming a relatively slender spring arm 46 having at its distal end an outwardly-turned spur 47 which projects slightly beyond the periphery of the shaft and which serves as a key as will presently be described. A retractor cam 48 extends trans-axially of the knob shaft through the recesses 42 and is attached, by rivets 49, to a cup-shaped retainer 51 which is positioned within the knob shaft. The opposite ends of the retractor cam extend radially of and for a considerable distance beyond the periphery of the shaft. The positioning of the retractor cam in the recesses 42 and the connection thereof with the retainer 51 prevents any movement of the cam either radially or axially of the knob shaft. Telescoping the end of the knob shaft, opposite to that in which the slot 41 is formed, and abutting against the end of the hub 31, is an extension tube 52 having in the wall thereof an aperture 53 into which the spur 47 of the knob shaft may be snapped so as to releasably key the latter shaft and the extension tube 52 together as an integral unit. Detachment of the extension tube from the knob shaft may be accomplished by inserting a slender rod or screw driver in the aperture 53 and depressing the lug 47 below the inner periphery of the extension tube whereupon the latter may be withdrawn axially from the end of the knob shaft. The outer end of the extension tube is provided with a concave keyway 54 in which is engaged the convex portion 55 of a corresponding keyway 56 formed at one end of a tubular bushing 57 which telescopes over the extension tube 52 and has its inner end journaled in the bore 37 of the escutcheon plate 36. The extension tube and the bushing 57 are thus secured together against relative rotation. The extension tube has therein an aperture 58 into which a tab 59 struck inwardly from the wall of the bushing 57 is pressed so that the latter tube and the extension tube are secured together against relative axial movement. The extension tube is provided with an elongated aperture 61 which registers with a corresponding opening 62, in the bushing 57, which has therein a slender spring arm 63 having at its distal end an outwardly-turned spur 64 which enters an aperture 66 formed in the tubular hub 67 of a knob 68. A protuberance 69, pressed inwardly from the wall of the knob hub 67, enters the keyway 56 and secures the knob and the bushing 57 together for rotary motion. The engagement of the spur 64 in the knob aperture 66 secures the knob and bushing together against relative axial displacement.

In the bore 21, as is best shown in Figure 8, is a tubular bolt housing 71 having at its outer end a radially extending flange 72, which lies at the bottom of a recess 73 formed in the edge of the door, and at its inner end a pair of integral

U-shaped guides 74 which project through the opening 23 in the side of the lock body and which extend into the latter nearly to its axis. A pair of angle clips 76, secured to the plate 26 by rivets 57, engage the guides 74 and prevent relative lateral spreading thereof. In the channels of the guides 74 is slidably mounted a crosshead 78, having at one end a pair of horizontal arms 79, which extend to points adjacent one side of the retractor cam 48, and at the other end a pair of ears 81 which support a pivot pin 82 passing transversely through one end of the bolt 83. The other end of the bolt 83 is provided with screw threads 84 engaged in mating threads 86 formed in an axial bore provided in a bolt head 87. A coil spring 88 has one end thereof seated in a peripheral notch 89, formed at one end of the bolt head, and the other end thereof seated in a circular groove 91 formed in a plate 92 which is pressed into the bolt housing 71. The plate 92 has a central opening through which the bolt 83 slidably passes. The bolt head 87 has the usual D-shaped cross-sectional form and is axially slidable in a corresponding D-shaped aperture formed in a plate 93 which is positioned in the recess 73 overlying the flange 72. Wood screws 94, which pass through suitable aligned apertures formed in the plate 93 and the flange 72, are screwed into the door 19 and hold the plate 93 and the bolt housing 71 in place. It will be seen that when the knob 68 is manually rotated in either direction, the retractor cam 48 will engage one of the arms 79 and will move the crosshead 78, against the tension of the spring 88, to retract the bolt head 87. The spring 88, when the knob is released, will return the bolt head to its normal extended position and the retractor cam 48 to its normal perpendicular position as shown in Figure 8. The crosshead is provided with a pair of notches 96 which, when the bolt head 87 is fully extended, are aligned with the notches 33 of the plate 26, and a plate 97, secured to the plate 26 by rivets 98, is provided with rimmed horizontal flanges 99 forming, in conjunction with the face of the plate 26, channel shaped guides into which the crosshead may pass when the latter is moved by the retractor cam.

Means is provided, operative from the side of the door opposite the knob 68, for moving the crosshead 78 to retract the bolt head 87. Mounted on and concentric with the slotted end of the knob shaft 39 is a bushing 101 over which is telescoped an extension tube 102, shown in detail in Figures 11 to 13 inclusive, having at one end a transaxial slot 103 through which a screw 104 passes, Figure 3, and is tapped into receiving holes formed in the bushing 101 and also in the knob shaft 39. The slot 103 extends over about one-fourth of the circumference of the extension tube. The screw 104 secures the knob shaft 39, the bushing 101 and the extension tube 102 together against relative axial movement but permits the extension tube to be rotated relative to the knob shaft within the limits of the slot 103 which is approximately 90 degrees. The other end of the extension tube is provided with a depressed keyway 106, a relatively long trans-axial tab 107 which is rolled at its extreme end to form a loop 108, a latch tab 109 which is struck radially inwardly from the wall of the tube, and an axially parallel opening 111 in which is disposed an integral relatively slender spring arm 112 provided with an outwardly directed lug 113. The extension tube is journaled

in the apertured hub 37 of a second escutcheon plate 36 which is secured by screws 114 to the side of the door; the threaded ends of the screws being engaged in the threaded bosses 34 of the plate 26. A knob 116 is provided, having its tubular hub 117 telescoped over the extension tube 102, the hub being provided with a protuberance 118, which enters the keyway 106 and secures the hub and extension tube for rotational movement together, and with an aperture 119 into which the lug 113 may be snapped to secure the hub and extension tube together against relative axial movement. The knob is also provided with a concentric opening 121. A coiled torsion spring 122, which is positioned within the extension tube 102, has one end engaged in the loop 108 and the other end anchored in a socket which is drilled into the end surface of the wall of the knob shaft 39. It will be seen that when the knob 116 is manually rotated, a rotational force will be transmitted through the spring 122 to the knob shaft thereby causing the latter to be rotated and move the retractor cam 48 to retract the bolt head 87. It is impossible to impress an excessive torsional strain on the spring 122 since, when the knob hub 117 rotates a certain degree relative to the extension tube, an end of the slot 103 will engage the screw 104 so as to effect a positive driving connection between the knob and the extension tube.

Means is provided for locking the knob shaft 39 against rotation so as to prevent retraction of the bolt head 87 and thus bar the door. Concentric with and extending into the slotted end of the knob shaft 39 is a ferrule 123 having a radially extending tab 124, which is engaged in the notch 43 at the end of the knob shaft, and an end wall 126 having a rectangular aperture 127 extending therethrough. Concentric with the ferrule 123, and extending for slidable movement through the aperture 127, is a pair of parallel metal strips forming a push rod 128, the strips being secured together at spaced intervals, by rivets 129, having at one end a T-shaped head, whose ends project transversely through the slot 41 and radially beyond the periphery of the knob shaft to form dogging keys 131, and having, as is best shown in Figure 7, portions 132 intermediate their ends which are relatively spaced so as to form a loop 133. The extreme outer end of the push rod is provided with transverse notches 134 which receive the end flanges 136 of a diametrically split head 137 which is pressed into a cup-shaped pushbutton 138 extending through and slidable in the knob aperture 121. A coil spring 139 encircling the pushrod 128 and positioned within the ferrule 123 engages, at one end, the wall 126 of the ferrule and, at the other end, a cup 141 engaging a pair of clips 142 which are secured to the pushrod by one of the rivets 129. It will be seen, by successively examining Figures 1 and 4, that, when the pushbutton 138 is manually depressed, the pushrod 128 will be moved longitudinally so as to move the dogging keys 131 into the notches 33 and 96 of the plate 26 and the crosshead 78 respectively. Since the position of the plate 26 is fixed and since the dogging keys 131 extend through the notches of this fixed element and enter the registered notches of the relatively movable crosshead, it will be seen that both the crosshead and the knob shaft 39 will be locked against movement. Of course, in the absence of means for retaining the dogging keys 131 in en-

gagement with the notches 33 and 96, when manual pressure is removed from the pushbutton 138, the compressed spring 139 will expand to draw the dogging keys out of the notches and unlock the knob shaft and the crosshead.

Means is provided for latching the dogging keys in engagement with the notches 33 and 96 so as to lock the door and means is also provided, operative upon rotational movement of one of the knobs, for releasing the dogging keys so as to unlock the door. Positioned in the loop 133 of the pushrod 128 is a latch lever 143 having an apertured ear 144 projecting from one side thereof, through which a rivet forming a pivot pin 146 passes, a downwardly extending finger 147 and a T-shaped head 148 which rests on the upper surface of the strips forming the pushrod. The T-shaped head 148 prevents downward pivotal movement of the latch lever beyond a predetermined point but permits unlimited upward movement thereof. A leaf spring 149 which has an end tab resting in a notch 151 formed in the upper surface of the pushrod, and which is anchored in place by an extension member 152 of one of the clips 142, has its other or free end resting on top of the head 148 so as to resiliently resist upward pivotal movement of the latching lever and to urge the head 148 into engagement with the pushrod. The finger 147 of the latching lever and the latch tab 109 of the extension tube 102 are so relatively positioned that the latter is in the path of movement of the finger 147 as the pushrod is moved longitudinally. When the pushbutton is depressed, in the act of locking the door, the finger 147, as is shown in Figure 2, will contact the latch tab 109 and will ride over and snap behind the latter, as shown in Figures 4 and 5, when the dogging keys 131 reach their positions in full engagement in the notches 33 and 96. The dogging keys are thus held in engagement with the notches and the door is securely locked against being opened by rotation of the outer knob 68. When it is desired to unlock the door, the inner or pushbutton knob 116 is grasped and manually rotated in either direction. This, as is shown in Figure 6, causes the latch tab 109, as the extension tube 102 is rotated by the knob, to move to either side from in front of the finger 147 thus freeing the latter and permitting the pushrod, under pressure of the spring 139, to return to its normal position wherein the pushbutton 138 is extended and the dogging keys 131 are out of engagement with the notches 33 and 96.

A feature of convenience present in the lock of my invention is that the bolt head 87 may, by depressing the pushbutton 138, be locked in extended position. It is thus impossible for anyone to jimmy the lock, as may be done with existing lock structures, by inserting a tool into the gap between the edge of the door and its frame so as to forcibly retract the lock bolt. Securing of the lock bolt in extended position also makes it possible to prevent an open door being accidentally slammed shut such as by a draft.

Having thus described my invention in detail, what I claim as new and desire to secure by Letters Patent is:

1. A lock comprising a lock body having a fixed element therein, a tubular knob shaft mounted for rotation in said lock body, said knob shaft having a longitudinally extending slot therein, a bolt housing extending radially

into and from said lock body, a bolt structure including a crosshead slidably mounted in said bolt housing adjacent and movable relative to said fixed element, a push rod in and extending axially of said knob shaft, said push rod having a dogging key thereon extending through the knob shaft slot and projecting radially beyond the periphery of the knob shaft, means connected with said push rod and extending beyond an end of said knob shaft for moving said push rod axially of the knob shaft and the dogging key into engagement with the fixed element and crosshead so as to secure the fixed element and crosshead together against relative movement, a latch lever carried by said push rod and engageable with a portion of said knob shaft, when the push rod is moved, for connecting the push rod and knob shaft together so as to retain the dogging key in engagement with the fixed element and the crosshead, and means associated with said knob shaft for releasing the engagement therewith of said latch lever.

2. A lock comprising a lock body having a fixed element therein, a tubular knob shaft mounted for rotation in said lock body, said knob shaft having a longitudinally extending slot therein, a bolt housing extending radially into and from said lock body, a bolt structure including a crosshead slidably mounted in said bolt housing adjacent and movable relative to said fixed element, a push rod in and extending axially of said knob shaft, said push rod having a dogging key thereon extending through the knob shaft slot and projecting radially beyond the periphery of the knob shaft, means connected with said push rod and extending beyond an end of said knob shaft for moving said push rod axially of the knob shaft and the dogging key into engagement with the fixed element and crosshead so as to secure the fixed element and crosshead together against relative movement, an extension tube concentric with and mounted for rotational movement on and with respect to said knob shaft, a latch lug extending radially from said extension tube, a latch lever pivotally mounted on and extending from said push rod and toward said latch lug, said latch lever, when the push rod is moved axially of the knob shaft, being adapted to ride over said latch lug and to snap into engagement with a surface of the latter so as to maintain the dogging key in engagement with the fixed element and the crosshead, and a knob secured to said extension tube for rotating said extension tube so as to move the latch lug from engagement with the latching lever.

3. A lock comprising a tubular lock body having therein an opening in its side wall and a fixed plate therein provided with a central opening having a peripheral lock notch, a tubular knob shaft mounted for rotation in said lock body and extending concentrically through said plate opening, said knob shaft having therein a longitudinally extending slot, a tubular bolt housing positioned axially perpendicular to said lock body, said bolt housing having thereon a pair of channel shaped guide extensions projecting through said side wall opening of the lock body and entering said lock body, a bolt structure in said bolt housing including a crosshead slidably mounted in said channel shaped guide extensions and movable diametrically across said plate opening, said crosshead having therein a lock notch registerable with the lock notch of the plate opening, a push rod in and extending axially of said knob shaft, said push rod having a dogging key

thereon extending through the knob shaft slot and projecting radially beyond the periphery of the knob shaft, a push button connected with an end of said push rod for moving the push rod axially of the knob shaft and the dogging key into engagement with the lock notches of the fixed plate and the crosshead so as to secure the fixed plate and the crosshead together against relative movement, an extension tube concentric with and mounted for rotational movement on and with respect to said knob shaft, a latch lug extending radially from said extension tube, a latch lever pivotally mounted on and extending from said push rod and toward said latch lug, said latch lever, when the push rod is moved axially of the knob shaft, being adapted to ride over said latch lug and to snap into engagement with a surface of the latter so as to maintain the dogging key in engagement in the lock notches of the fixed plate and the crosshead, and a knob secured to said extension tube for rotating said extension tube so as to move the latch lug from engagement with the latching lever to permit withdrawal of the dogging key from engagement in the lock notches of the fixed plate and the crosshead.

4. A lock comprising a tubular lock body having a fixed plate therein provided with a central opening having a peripheral lock notch, a tubular knob shaft mounted for rotation in said lock body and extending concentrically through said plate opening, said knob shaft having therein a longitudinally extending slot, a tubular bolt housing positioned axially perpendicular to said lock body, said bolt housing having thereon a pair of channel shaped guide extensions projecting through said side wall opening of the lock body and entering said lock body, a bolt structure in said bolt housing including a crosshead slidably mounted in said channel shaped guide extensions and movable diametrically across said plate opening, said crosshead having therein a lock notch registerable with the lock notch of the plate opening, a push rod in and extending axially of said knob shaft, said push rod having a dogging key thereon extending through the knob shaft slot and projecting radially beyond the periphery of the knob shaft, a push button connected with an end of said push rod for moving the push rod axially of the knob shaft and the dogging key into engagement with the lock notches of the fixed plate and the crosshead so as to secure the fixed plate and the crosshead together against relative movement, an extension tube concentric with and mounted for rotational movement on and with respect to said knob shaft, a torsion spring connected at its respective ends to said extension tube and to said knob shaft, a latch lug extending radially from said extension tube, a latch lever pivotally mounted on and extending from said push rod and toward said latch lug, a leaf spring mounted on said push rod and engaging said latch lever for resiliently resisting pivotal movement of the latch lever, said latch lever, when the push rod is moved axially of the knob shaft, being adapted to ride over said latch lug and to be snapped, by the said leaf spring, into engagement with a surface of the latch lug so as to maintain the dogging key in engagement in the lock notches of the fixed plate and the crosshead, and a knob secured to said extension tube for rotating said extension tube so as to move the latch lug from engagement with the latching lever to permit withdrawal of the dogging key from engagement in the lock notches of the fixed plate and the crosshead.

5. A lock comprising a lock body having a fixed element therein, a tubular knob shaft mounted for rotation in said lock body and comprising a plurality of separate sections, one section of said knob shaft having a longitudinally extending guide therein, a bolt housing extending radially into and from said lock body, a bolt structure including a crosshead slidably mounted in said bolt housing adjacent and movable relative to said fixed element, a push rod in and extending axially of said knob shaft, said push rod having a dogging key thereon engaging the guide, and projecting radially beyond the periphery, of said one section of the knob shaft, means connected with said push rod for moving said push rod axially of the knob shaft and the dogging key into engagement with the fixed element and the crosshead so as to secure the fixed element and crosshead together against relative movement, a latch lug carried by and extending radially from another section of said knob shaft, a latch lever mounted for movement on and relative to said push rod and extending toward said latch lug, said latch lever, when the push rod is moved axially of the knob shaft, being adapted to pass over and into latched engagement with the latch lug so as to maintain the dogging key in engagement with the fixed element and the crosshead, and means for rotating said other section of the knob shaft so as to relatively displace the latch lever and latch dog and thereby release the engagement thereof.

6. A lock comprising a lock body having a fixed element therein, a tubular knob shaft mounted for rotation in said lock body and comprising a plurality of of separate sections, one section of said knob shaft having a longitudinally extending guide therein, a bolt housing extending radially into and from said lock body, a bolt structure including a crosshead slidably mounted in said bolt housing adjacent and movable relative to said fixed element, a push rod in and extending axially of said knob shaft, said push rod having a dogging key thereon engaging the guide, and projecting radially beyond the periphery, of said one section of the knob shaft, means connected with said push rod for moving said push rod axially of the knob shaft and the dogging key into engagement with the fixed element and the crosshead so as to secure the fixed element and crosshead together against relative movement, a latch lug carried by and extending radially from another section of said knob shaft, a latch lever mounted for movement on and relative to said

push rod and extending toward said latch lug, said latch lever being in alinement, axially of the knob shaft, with the latch lug and, when the push rod is moved axially of the knob shaft, being adapted to pass over and into latched engagement with said latch lug so as to maintain the dogging key in engagement with the fixed element and the crosshead, means for rotating said other section of the knob shaft so as to relatively rotationally displace the latch lever and the latch lug and thereby release the engagement thereof, and means resiliently connecting said sections of the knob shaft together.

7. A lock comprising a lock body having a fixed element therein, a tubular knob shaft mounted for rotation in said lock body and comprising a plurality of separate sections, one section of said knob shaft having a longitudinally extending guide therein, a bolt housing extending radially into and from said lock body, a bolt structure including a crosshead slidably mounted in said bolt housing adjacent and movable relative to said fixed element, a push rod in and extending axially of said knob shaft, said push rod having a dogging key thereon engaging the guide, and projecting radially beyond the periphery, of said one section of the knob shaft, means connected with said push rod for moving said push rod axially of the knob shaft and the dogging key into engagement with the fixed element and the crosshead so as to secure the fixed element and crosshead together against relative movement, a latch lug carried by and extending radially from another section of said knob shaft, a latch lever mounted for movement on and relative to said push rod and extening toward said latch lug, said latch lever being in alinement, axially of the knob shaft, with the latch lug and, when the push rod is moved axially of the knob shaft, being adapted to pass over and into latched engagement with said latch lug so as to maintain the dogging key in engagement with the fixed element and the crosshead, means for rotating said other section of the knob shaft so as to relatively rotationally displace the latch lever and the latch lug and thereby release the engagement thereof, and a spring interposed between said sections of the knob shaft for resiliently connecting said sections of the knob shaft together and for resiliently maintaining the alinement of said latch lug and said latch lever.

JOHN F. CHING.
